[57] CLAIM

The ornamental design for a multi-purpose tool, substantially as shown.

DESCRIPTION

FIG. 1 is a side elevation of the multi-purpose tool;

FIG. 2 is a top plan view of the tool;

FIG. 3 is a side elevation of the tool when looking at the opposite side from that shown in FIG. 1;

FIG. 4 is an end view of the tool when looking at the left hand end of FIG. 3;

FIG. 5 is an end view of the tool when looking at the right hand end of FIG. 3;

FIG. 6 is a bottom plan view of the tool; and

FIG. 7 is a transverse section through the tool and is taken along the line 7—7 of FIG. 6.
